(57) **CLAIM**

The ornamental design for a collet, as shown and described.

DESCRIPTION

FIG. 1—is a front perspective view of a collet showing my new design;

FIG. 2—is a side elevational view thereof;

FIG. 3—is an elevational view of the opposite side of FIG. 2;

FIG. 4—is a top view thereof;

FIG. 5—is a bottom view thereof;

FIG. 6—is a top view of a second embodiment showing my new design;

FIG. 7—is a top view of a third embodiment showing my new design;

FIG. 8—is a top view of a fourth embodiment showing my new design;

FIG. 9—is a top view of a fifth embodiment showing my new design; and,

FIG. 10—is a top view of a sixth embodiment showing my new design.

The side elevational and bottom views of embodiments 2-6 are identical to the views shown in FIGS. 2, 3 and 5.
